UNITED STATES PATENT OFFICE.

FREDERICK A. HART, OF NEWARK, NEW JERSEY, ASSIGNOR, BY MESNE ASSIGNMENTS, TO UNDERWOOD COMPUTING MACHINE COMPANY, OF NEW YORK, N. Y., A CORPORATION OF NEW YORK.

COPY-HOLDER FOR TYPE-WRITING MACHINES, &c.

1,245,909.

Specification of Letters Patent.

Patented Nov. 6, 1917.

Original application filed June 3, 1910, Serial No. 564,838. Divided and this application filed January 23, 1913. Serial No. 743,727.

To all whom it may concern:

Be it known that I, FREDERICK A. HART, a citizen of the United States, residing in Newark, in the county of Essex and State of New Jersey, have invented certain new and useful Improvements in Copy-Holders for Type-Writing Machines, &c., of which the following is a specification.

This invention relates to a folding copy holder adapted to form an attachment for a stand or table, such as a stand for a typewriter, adding machine, or other machine, and also usable in other ways.

The invention provides a copy holder, which, when not in use may be supported compactly in a pendent position, as for instance it may hang at the side of the stand or other device to which it is attached, and may be quickly adjusted to an elevated position for use.

The copy holder may comprise a frame portion, to which is pivotally mounted a leaf portion or support for the copy, and said leaf when not in use may lie about in the plane of the frame. The frame may be pivoted to a support, as for instance, a stand, and may be supported thereby in a pendent position when not in use, and may be swung up to a horizontal position for use, and the copy-supporting leaf may then be tilted on its frame to an upwardly and rearwardly inclined position, in which it may be retained by a supporting leg attached to the rear end of the leaf. Said leg may be provided with a notch to engage the frame when the leaf is lifted, and a spring may throw said leg upwardly beneath the leaf when the latter is lowered within the frame. Clamps to hold the copy against said support may be mounted on the front end of the frame to overhang said support, and swing therewith, thereby to hold the copy when the support is in either position. A line indicator extending laterally over the copy-holding support may be adjustably mounted on a bar extending along the edge of the support.

Other objects and advantages will hereinafter appear.

50 In the accompanying drawings,

Figure 1 is a front view of a table or typewriter stand equipped with the inven-

tion, the leaves being shown raised, in full lines.

Fig. 2 is a plan of Fig. 1.

Fig. 3 is an enlarged detail edge view of a copy holder raised, partly broken away to show the copy-holder, dotted lines showing the position of the copy holder when lowered.

Fig. 4 is a section of a copy holder on line *a-a* of Fig. 2, dotted lines showing the position of the copy-holder and its support in operative positions.

Fig. 5 is a detail cross-section on line *w-w* of Fig. 4, of the handle by which the line-indicating finger is operated.

Fig. 6 is a side view of the hinge-connection between the bracket and supporting leg of the tilting copy-holder, parts being shown in section.

Fig. 7 is a plan of the same, partly broken away to show the construction.

Fig. 8 is a fragmentary cross-section, showing the position of the copy-holder frame and its supporting latch when the frame is raised and while the latch is out of engagement with its stationary catch.

Fig. 9 is a detail section taken on line *y-y* of Fig. 3, showing the paper clamp on the copy-holder.

Fig. 10 is a horizontal cross-section on line *z-z* of Fig. 1, looking in the direction of the arrow, showing the hinge between the copy-holder frame and the stand.

Fig. 11 is a detail perspective view of the frame supporting latch, rock shaft and frame, at a point when the frame is intermediate its operative and idle positions, showing the latch pressed against the catch to act as a brake.

This application is a division of my application No. 564,838, filed June 3, 1910, which application eventuated in Patent No. 1,063,877 of June 3, 1913.

The stand or table A comprises suitably braced front and rear legs 6 and 7, supporting a skeleton bed or top 9, having outwardly projecting brackets 9^a by which the bed is connected to the legs. Lugs 9^a project from the bed into the central space enclosed thereby, to support a writing or adding machine 45 (indicated by dotted lines in Figs. 1 and 2).

As will be seen, the machine 45 occupies practically the entire table top; and to provide a support for books or papers from which the operator desires to copy, I have contrived a copy holder 2, 17, readily attachable to the stand, to fold or swing downwardly from its operative position. The copy holder at the left (in the drawings), comprises a frame 2, 2^a, 2^b, carrying a leaf 17 for supporting the copy, said frame being rigidly connected by a pair of supporting arms 3, 3^a, to a pintle or rock shaft 4 journaled in bearings 5, (see Fig. 10), formed in collars 8, attached to and detachable from the forward and rear legs 6, 7 (usually tubular) at one side of the stand below the brackets 9^b.

No special skill is required in attaching the copy holder to the stand, it being simply necessary to tighten the collars firmly on the legs.

The collars 8 are secured to the legs below the table top, and the copy-holder frame 2 is carried at the outer ends of the supporting arms 3, 3^a, which project from the rock shaft between the brackets 9^b, and support the frame when elevated, about on a plane with the top 9 of the stand.

By hinging the frame 2 as shown, with the pintle 4 at or near the inner sides of the legs 6, the copy holder when in disuse, is caused to lie closely against the table, making a compact structure; while the arms 3 and 3^a extend up far enough from the hinge to give the desired elevation to the frame when in working position; said arms 3 and 3^a also permitting the copy holder to hang about vertically on the outer sides of the legs, as seen in dotted lines, at Fig. 1.

It will be seen that the inner edge of the copy holder when extended, lies closely adjacent to the side of the table top 9 to prevent articles from falling down between the top and the holder.

To hold the copy-holder frame up, a latch 10 is secured rigidly thereto, the lower free end of said latch 10 engaging a catch 11 mounted on the stand, said catch consisting of a nut threaded on the bolt 13, which secures one of the collars 8 on a leg of the stand. The frame is swung up until the latch 10 escapes the catch (Fig. 8), whereupon a spring 14 shifts the frame, with its supporting arms 3, 3^a and the pintle or rock shaft 4, in the bearings 5, bodily toward the right (Figs. 4 and 8), so that the foot 15 of the latch locks over the catch and supports the frame. The latch may have a stop 16, pressed by the spring 14 against the catch or abutment 11.

The latch 10, which may project from one of the arms 3, is preferably arc-shaped, as shown in Fig. 11, and concentric with the hinge pintle, to bear against the catch while the frame is being swung upwardly, and

thereby prevent the lateral shifting of the frame by the spring until it has been fully raised. A brace 10^a to strengthen the latch, may extend from the free end of the latter to the rock shaft 4.

To drop the frame, it is first pressed edge-wise toward the left, (Fig. 4), against the tension of spring 14, and caused to rise slightly, so as to release the latch 10 from the catch 11, as shown in Fig. 8. The catch 11 and latch foot 15 may be beveled to facilitate this releasing operation. The frame may now drop freely; the latch 10 acts also as a brake, the spring 14 pressing the side of the latch against the outer face of the catch, as in Fig. 11, throughout the entire downward swing of the frame to inoperative position, to retard the descent of the frame, and prevent it from hanging against the stand.

The copy-holder leaf or plate 17, is hinged to one end 2^a of the frame 2, as by straps 18, to enable the copy-holder plate to be inclined or tilted on its frame (see dotted lines, Fig. 4), the edge of the plate being rolled over a wire 17^a for rigidity. A bracket 23 on the copy-holder plate engages the opposite end 2^b of the frame to limit the swing of the plate.

The copy-holder plate 17 is raised to the position shown in dotted lines in Fig. 4, by a handle 24, the plate pulling with it a supporting leg 25, pivotally connected to the bracket 23 by a bolt 30 and nut 29, said leg being drawn across the end 2^b of the frame until a recess 27 at the free end or foot 26 of the leg catches over said end. To lower the copy-holder plate or leaf 17, the leg is disengaged from the frame.

The leg may be pressed against the frame end 2^b by a spring 28 as the leaf 17 is raised, to insure that the recess 27 shall catch over said frame end. Said leg is connected to the bracket so as to lie against the outer face of the frame end 2^b, and when the leaf 17 is lowered, the spring operates to swing the leg up under the frame 2, 2^b, where it is out of the way, (full lines, in Fig. 4), and by clasping the frame end 2^b between itself and the bracket 23, operates to lock the holder leaf against accidental tilting, when the frame 2 is dropped. The tension of the spring 28 is regulated by the nut 29, to which one end of the spring is connected, the opposite end being connected to the leg (as shown in Figs. 6 and 7), said nut being held where adjusted by a pin 31 seated in the bracket and fitting any one of a series of notches 32 in the nut.

A finger 33 extends across the copy-holder to enable the operator to readily follow the copy. Said finger is connected by a sleeve 34 to rock upon and slide along a helix or screw constituting a cylindrical rack 35 at one side of the copy-holder, and has a handle 37 whose hub 38 is slidable on the

rack and accommodated in a recess in the sleeve 34, said handle being foldable, as shown in dotted lines in Fig. 3, for compactness. The handle is arrested in operative position, (Fig. 5), by flattening the hub as at 41, to engage the wall of the slot in the sleeve 34. A spring-pressed detent 39 co-operating with the rack teeth 40, prevents accidental movement of the line indicator.

10 A paper clamp 19 swings on the shaft 2^a of the frame, to tilt with the copy-holder and to catch over the bottom edge of the paper thereon, said clamp having a handle 20. A boss 21 on the clamp bears upon the 15 walls of a groove 22 in the shaft 2^a to hold the clamp frictionally where adjusted.

The opposite side of the stand may be equipped with a drop leaf, if desired, that shown comprising a frame 42, 42^a, 42^b hinged 20 to the stand, similarly to the frame 2, and carrying a plate 43 fixed thereto by the clips or straps 44.

Variations may be resorted to within the scope of the invention, and portions of the 25 improvements may be used without others.

Having thus described my invention, I claim:

1. A copy holder comprising the combination of a frame, a leaf for supporting 30 copy pivoted to one end of the frame, a bracket secured to the leaf adjacent to the opposite end of the frame, a leg pivoted to said bracket and extending over the end of the frame and lying against the leaf on the 35 side opposite said bracket, a spring to hold the leg in said position, and means on said leg to engage the frame and hold the leaf in an inclined position.

2. A copy holder comprising, in combination, a frame and a copy-holding leaf or support hinged to the frame to swing into and out of an inclined position, means to releasably maintain said support in an inclined position relatively to the frame, and 45 a paper clamp hinged to turn on the frame and catch over the support in either position of the latter.

3. The combination with a frame, of a leaf for supporting copy, said leaf hinged to 50 one end of the frame, a paper clamp hinged to said end of the frame and extending over said leaf, and a support connected to the leaf and formed to engage the opposite end of the frame when the leaf is tilted thereon, and thus maintain the leaf in a tilted position.

4. A copy holder comprising, in combination, a frame adapted to be arranged horizontally for use, a leaf supporting copy,

said leaf hinged at one end to said frame 60 to swing upwardly therefrom to operative position, means carried by said leaf to support it in its operative position, and a paper clamp hinged to the frame to engage copy on said leaf in both positions of the 65 latter.

5. A copy holder forming an attachment for a stand or table, said holder comprising a frame forming the outline thereof, and a body forming a support for copy, said body 70 pivoted to the front end of the frame, so that its rear end may swing upwardly, whereby said support is upwardly and rearwardly inclined, a supporting leg pivotally connected with said body, and a spring to 75 hold said leg in engagement with the frame when said body is in said tilted position, said spring operable to swing said leg inwardly and upwardly beneath said body when the latter returns to a non-tilted position within the frame.

6. A copy holder forming an attachment for a stand or table, said holder comprising a frame forming the outline thereof, and a body forming a support for copy, said support pivoted at its forward end to the front end of said frame to permit said body to be tilted relatively to the frame to an upwardly and rearwardly inclined position, means to support said body in said inclined position, 90 and a work-holding clamp pivoted on the front end of the frame and extending rearwardly to overhang said body and clamp work thereon, said clamp arranged to swing on the frame as said body is tilted, and thereby retain its operative relation to said body for both positions of the latter.

7. A copy holder forming an attachment for a stand or table, said holder comprising a frame and a body portion forming a support for copy, said support hinged to the front end of the frame and lying within the frame, so that the upper surface of the support and frame lie about in the same plane, a supporting leg pivotally connected 100 to the said support at the rear end thereof, said leg formed with a holding notch or hook to engage the frame and hold said support in an inclined position, and a spring 105 to throw said leg upwardly and forwardly 110 to a substantially horizontal position beneath said support when the latter is swung down to the plane of the frame.
